UNITED STATES PATENT OFFICE.

JOHN B. HADAWAY, OF SWAMPSCOTT, MASSACHUSETTS, ASSIGNOR TO UNITED SHOE MACHINERY COMPANY, OF PATERSON, NEW JERSEY, A CORPORATION OF NEW JERSEY.

MACHINE FOR USE IN THE MANUFACTURE OF WELT-SHOES.

1,093,697.

Specification of Letters Patent.

Patented Apr. 21, 1914.

Application filed October 3, 1910. Serial No. 585,163.

To all whom it may concern:

Be it known that I, JOHN B. HADAWAY, a citizen of the United States, residing at Swampscott, in the county of Essex and State of Massachusetts, have invented certain Improvements in Machines for Use in the Manufacture of Welt-Shoes, of which the following description, in connection with the accompanying drawings, is a specification, 10 like reference characters on the drawings indicating like parts in the several figures.

This invention relates to machines for use in the manufacture of boots and shoes and particularly to a machine which is adapted 15 for operation upon a shoe after the welt has been attached for the purpose of shaping the welt and adjacent portions of the shoe.

It has been discovered that after the welt has been attached to the shoe by the inseam 20 the welt may not only be beaten out to flatten it and be slit at certain portions of the shoe to facilitate the flattening operation but it may also advantageously be extended widthwise. I find that it is practical to extend a welt in the direction of its width a substantial extent by properly pulling and rubbing it in the direction outwardly away from the shoe. I find that by the use of the 25 present invention the welt itself and the inseam are actually improved and the shoe is given a better appearance by subjecting the shoe to the described action. It has been proposed to substitute for the knife of the commercial welt beating and slashing machine, shown in my Letters Patent No. 30 875,171, a pair of gripping members which were to be arranged between the hammer and the work support upon which the welt is rested as an anvil. These proposed gripping devices or clappers would separate the 35 welt from the hammer and the anvil and prevent direct engagement of the beating devices with the welt and it would be impossible to employ with such an arrangement the 40 welt slitting knife which is regarded as essential to a practical machine.

In accordance with an important feature of the illustrated embodiment of this present invention a welt beating hammer directly engages the welt and has in addition to its movement in the direction to beat the 50 welt a movement over the welt in pulling or rubbing contact with the welt. Also in this embodiment of the invention the hammer is

actuated toward the welt by a lever which 55 has a fixed fulcrum and to which the hammer is pivotally connected for swinging movement by means other than the lever while the hammer is in contact with the work. In the construction shown, the hammer is connected to the lever through a spring which is compressed by the last portion of the lever's down-stroke and provides a dwell of the hammer upon the work. Advantage is taken of this dwell to actuate the 60 hammer outwardly as the hammer pressure increases whereby to exert an outward pull on the welt and to actuate the hammer further outward in rubbing contact with the 65 welt as the lever rises and the spring expands to lighten the hammer pressure.

A further important feature of this invention is found in the combination by which is made possible for the first time in one machine the three functions of beating, 70 extending or stretching and slitting the welt in a single operation.

These and other features of this invention, including certain combinations of parts and more important features of construction will more fully appear in connection with the following description of the machine in which I have chosen to illustrate the invention for the purpose of explanation, 75 and will then be pointed out in the claims.

Figure 1 is a side elevation of a machine equipped with this invention. Fig. 2 is a section on line 2-2, Fig. 3. Fig. 3 is a fragmentary view showing the relation of the work at the end of a hammer stroke. 80 Fig. 4 is a section on line 4-4 of Fig. 2; Fig. 5 is a section on line 5-5 of Fig. 3.

The illustrated embodiment of the invention comprises a welt beating hammer 1 having a cavity 2 cut in its face to permit the 85 access of the knife 20 to the welt while under compression by the hammer. The hammer is mounted upon the stem 3 carried by the hammer lever 6 of the machine. A spring 4 received within the carrier of the hammer 90 engages a shoulder on the hammer stem and normally operates to hold the hammer at the limit of its downward movement determined by the adjustable stop collar 5 which consists of a split nut secured upon the stem 3. 95 The lever 6 is fulcrumed at 7 and has its rear end forked to embrace the block 10 of an eccentric 11 on the main shaft 12 of the

machine. A work support 15 is provided which is projected from a bar 16 having an adjustable connection with the top face of an arm of the machine frame. The work support is shaped to enter the welt crease of a welted shoe and to support the welt as near as practicable to the inseam. The welt slitting knife 20 is supported by a carrier 21 which is mounted to be reciprocated forwardly and backwardly in a guideway in a plate 24 by a lever 28 which carries a block confined in a slotted portion of the lever. The lever is fulcrumed at its lower end at 29 to the frame and it carries a roll 30 which stands in the path of a cam 32 rotated on a stub shaft 33 by a worm wheel 34 driven from a worm 35 on the main shaft 12. The cam is connected to the worm wheel by a clutch of the sliding bolt variety controlled by a lever 49 pivoted at 50 and normally held by a spring 51 in position to hold the clutch open and the cam at rest. A treadle 52 is provided to close the clutch connection and cause the knife to be driven in appropriate time relation to the hammer when it is desired to slit the welt. The knife and its actuating mechanism might be omitted if not required.

The machine as thus far described is or may be substantially like that shown in my prior Letters Patent No. 875,171 to which machine the present improvement is applied.

The hammer with its stem 3 is mounted in a carrier 60 which is pivotally connected with the lever 6 by trunnions 62 and said carrier also has connection below said trunnions with the forward, nearly horizontal arm of a bell crank lever 65 the upwardly projecting arm of which is connected by a rod 66 to the eccentric block 10 whereby actuation of the bell crank 65 and of the hammer carrier 60 is effected in time relation to the beating movements of the hammer. These connections move the hammer rearwardly or toward the outer edge of the welt while the hammer is in engagement with the welt. More specifically stated, the eccentric has little effect on the bell crank during the major part of the hammer's downward movement or until the eccentric block starts backwardly whereupon it begins to move the bell crank in the direction to draw the hammer over the welt toward the edge of the welt first slowly and then more rapidly and continues to draw it rearwardly during the first half of the movement of the eccentric for raising the hammer carrying end of lever 6. The stop collar 5 is usually adjusted so that the hammer strikes the work a substantial time before the end of the down-stroke of its end of the lever 6 and the spring 4 yields to allow the lever to complete its stroke. This provides for a dwell of substantial duration of the hammer upon the work during the last part of the down-

stroke of the lever 6 and the first portion of its upstroke. It is during this period of engagement of the hammer with the work that the bell crank effects backward swinging of the hammer carrier. The extent of this backward or swinging movement of the hammer head is variable by an adjustable connection between the bell crank 65 and the link 64. The link and the connected arm of the bell crank form in effect a toggle which as it is "broken" begins slowly to pull the hammer carrier rearwardly over the welt and rapidly increases this action to the end of its breaking stroke. The bell crank arm has a vertical slot in which the pivot pin connecting it to the link 64 is adjustable upwardly or downwardly with relation to the fulcrum of the bell crank to initiate and carry on the movement of the hammer head more or less rapidly. The effect of this backward movement of the hammer carrier is to rub the welt in the direction of its width and exert a drawing action which perceptibly extends the welt widthwise. This extension of the welt appears to be due to three causes: The welt is straightened outwardly to overcome the effect of any contraction which may have occurred in the welt attaching operation, as for example, in bending the welt around the convex portions of the shoe edge; the welt is stretched widthwise more or less by the drawing effect of the hammer as it rubs over the welt under the pressure of the spring 4; and finally the outward pull on the welt seems to draw down upon the upstanding inner edge portion of the welt which is attached to the upstanding lip of the innersole. This last not only lets the welt pull outwardly farther but it also has a beneficial effect upon the inseam in that it draws the seam down flatter and the upstanding portion of the welt seems to exert a leverage tending to close the spaces between the welt, upper and lip in the trimmed face of the inseam.

By the use of this invention a narrower welt can be used in a shoe, and the appearance of the shoe is improved both by getting a closer and a flatter inseam and by smoothing and firming the welt. Another practical advantage found in the use of this machine is that the action of the hammer in its crosswise movement with, and relatively to, the welt tends to hold the shoe in the machine, thus materially assisting the operator in his work by relieving him from considerable exertion in holding the shoe which he had to use in prior types of welt beating machines. The hammer may advantageously be arranged to extend over the work beyond the work support and to engage the between-substance of the shoe on the upturned edge faces of the welt, upper, and innersole lip. By this engagement these edge portions of the shoe stock are depressed

to the level of the face of the welt so that the outersole may lie flat upon them and upon the welt. This beating action on the trimmed inseam or the between-substance is 5 saved from being too severe by the fact that the last, or the shoe as a whole, is not rigidly supported but only the welt rests on the anvil as appears from the drawings. Also, the movement of the hammer laterally in contact with these faces assists in extending the 10 welt or tends to draw this portion of the shoe stock outwardly and to the outermost limit which any existing slackness will permit.

15 The opening 2 in the hammer head through which the knife 20 works has converging side walls as appears from Fig. 5 in which the hammer is shown in section looking upwardly. As the hammer is moved 20 outwardly in contact with the welt the edges of the converging walls rub upon the welt and increase the width extending action of the hammer and also the tendency of the hammer to keep the shoe pressed toward the 25 machine. The hammer is rapidly driven so that as the welt is fed along under it portions of the surface of the welt which are closely adjacent to each other are subjected to this drawing action of the hammer face.

30 Having explained the nature of this invention and described a preferred construction embodying the same I claim as new and desire to secure by Letters Patent of the United States all the protection thereon 35 which I am entitled to under the statutes in view of the prior art, and the following claims are to be construed broadly to give effect to this intention:

1. A welt beating machine having, in 40 combination, a support for the welt, a lever, a hammer carried by the lever and connected therewith at a fixed distance from the fulcrum of the lever, means for operating the lever to cause the hammer to beat the 45 welt, and means for moving the hammer relatively to the lever in a direction widthwise of the welt while it is in beating engagement with the welt.

2. A welt beating machine having, in 50 combination, a work support upon which the welt directly rests, a hammer, a lever carrying the hammer and having a fixed fulcrum, an axis fixed in the lever and about which the hammer can turn, means for 55 oscillating the lever about said fulcrum to cause the hammer to beat the welt, and additional means to move the hammer about said axis to cause it to draw out the welt widthwise.

60 3. A welt beating machine having, in combination, a work support upon which the welt directly rests, a hammer, a holder in which the hammer is yieldingly mounted, a lever carrying the holder and a connection 65 between the lever and the holder per-

mitting turning movement only of the holder relatively to the lever, means for oscillating the lever to cause the hammer to beat the welt, a spring between the hammer and said actuating means to be compressed when the hammer strikes the welt and while the actuating means completes its stroke whereby the hammer has a dwell upon the work, and additional means to actuate the hammer toward the body of the 75 machine during the said dwell.

4. A welt beating machine having, in combination, a work support upon which the welt directly rests, a hammer having direct engagement with the welt, a lever 80 carrying the hammer, connections permitting turning movement of the hammer and preventing forward and backward sliding movement thereof on the lever, means for oscillating the lever, said machine being 85 constructed and arranged to cause the hammer to have a dwell upon the work, and means to actuate the hammer outwardly over the welt in the direction toward the 90 welt edge during said dwell.

5. A welt beating machine having, in combination, a work support upon which the welt directly rests, a hammer directly engaging the welt, a lever carrying the hammer, connections permitting endwise sliding 95 and forward and backward turning movements of the hammer and arranged to prevent forward and backward sliding movements thereof on the lever, means for actuating the lever, a spring between the hammer and said actuating means to be compressed during the last portion of the downstroke of the lever and to expand during the first portion of the upstroke while the hammer is in contact with the welt, and means to actuate the hammer outwardly from the shoe during said compression of the spring to pull the welt relatively to the shoe and to continue the upward movement of the hammer in rubbing contact with the welt during 100 the expansion of the spring.

6. A welt beating machine having, in combination, a work support upon which the welt directly rests, a beating hammer directly engaging the welt, a lever carrying 115 the hammer, pivotal connections fixed in the lever and permitting turning and endwise yielding of the hammer, actuating means having provision for causing a dwell of the hammer upon the work during which 120 the beating pressure is increased to its maximum and then decreased, and means to move the hammer outwardly from the shoe during said period of increasing pressure and farther outwardly and over the welt 125 during the period of decreasing pressure.

7. A welt beating machine having, in combination, a work support upon which the welt directly rests, a beating hammer directly engaging the welt, a lever carrying 130

the hammer and having a movable connection with the hammer in fixed relation to the length of the lever, and means for actuating the hammer in the plane of the work 5 relatively to the lever during its beating engagement with the work.

8. A welt beating machine having, in combination, a work support upon which the welt directly rests, a beating hammer directly engaging the welt, a hammer holder 10 having trunnions, a lever having bearings in which the trunnions closely fit, means for actuating the lever, and means for swinging said hammer about said connection with the 15 lever while it is in contact with the welt.

9. A welt beating machine having, in combination, a work support upon which the welt directly rests, a beating hammer directly engaging the welt, a lever carrying 20 the hammer, a fixed pivot in the lever about which the hammer has turning movement, means to actuate the lever to effect beating of the welt, and other means to actuate the hammer widthwise of the welt while in engagement with the welt.

10. A welt beating machine having, in combination, a work support upon which the welt directly rests, a beating hammer directly engaging the welt, a lever carrying 25 the hammer, a pivot fixed in the lever and about which the hammer can swing, means for actuating the lever, and means operating in time relation to the lever movements to swing the hammer outwardly over the 30 welt during the last portion of its down-stroke and the first portion of its up-stroke.

11. A welt beating machine having, in combination, a work support, a hammer, a lever to actuate the hammer, an eccentric to 40 actuate the lever vertically, and a connection from the eccentric to the hammer arranged to actuate the hammer in the direction of the width of the welt while the hammer is in beating engagement therewith first 45 slowly and then more rapidly.

12. A welt beating machine having, in combination, a work support, a hammer, a lever to actuate the hammer, an eccentric to actuate the lever vertically, and a connection 50 from the eccentric to the hammer to actuate the hammer horizontally, said connection being arranged to give maximum horizontal movement at about the ends of the vertical strokes of the hammer.

13. A welt beating machine having, in combination, a work support, a hammer, a lever to actuate the hammer vertically, a drive shaft, a bell crank, a connection from the bell crank to the shaft, and a connection 60 from the bell crank to the hammer to impart horizontal movements to the hammer.

14. A welt beating machine having, in combination, a work support, a hammer, a lever to actuate the hammer vertically, a drive shaft, a bell crank, a connection from 65

the bell crank to the shaft, and a connection from the bell crank to the hammer to impart horizontal movements to the hammer, one of said connections being adjustable to vary the horizontal movements of the 70 hammer.

15. A welt beating machine having, in combination, a work support, a hammer, a lever to actuate the hammer vertically, a drive shaft connected to said lever, a pivotal connection between the hammer and the lever, a bell crank having a vertical arm connected with the drive shaft and a horizontal arm, and a link connecting the hammer to the latter arm and forming therewith a substantially straight toggle to be broken for moving the hammer outwardly over the welt first slowly and then more rapidly, substantially as described. 75 80

16. A welt beating machine having, in combination, a work support, a hammer, means to actuate the hammer downwardly to beat the welt, means to actuate the hammer outwardly to stretch the welt, and means to slit the welt. 85

17. A welt beating machine having, in combination, a hammer, means to actuate the hammer to beat the welt after attachment to the shoe, means to actuate the hammer to extend the welt widthwise, means for forming 95 in the welt a series of slits, and means to throw the slitting means into and out of operation during the continued operation of the hammer. 90

18. A welt beating machine having, in combination, a hammer, means for actuating the hammer to beat the welt, a work support shaped to support the welt after attachment to the shoe, a welt slitting knife, driving means, and connections therefrom to 105 actuate the knife to slit the welt and to actuate the hammer to rub the welt both while the welt is clamped between the hammer and the work support. 100

19. A welt beating machine having, in combination, a work support, a hammer, means to actuate the hammer to beat the welt, a knife, means to actuate the knife to slit the welt, and additional means to actuate the hammer to stretch the welt. 110

20. A welt beating machine having, in combination, a frame, a work support providing an anvil upon which to beat the welt and a lateral rest for the shoe, a hammer, a knife, means to actuate the hammer to beat the welt, means to actuate the knife to slit the welt, and additional means to actuate the work support and the hammer relatively in a direction substantially parallel to the face of the welt while the welt is clamped 120 125 between them. 115

21. A welt beating machine having, in combination, a support for the welt, a hammer carrier, a hammer, means having pivotal connection with the carrier at a fixed 130

- point and movable to cause the hammer to beat the welt, and means for giving the hammer an additional movement in a direction widthwise of the welt.
- 5 22. A welt beating machine having, in combination, an anvil constructed and arranged to extend under the welt and into the welt crease to support the major portion of the width of the welt, a beating hammer 10 movable from and toward the anvil and constructed and arranged to engage the portion of the welt that rests upon the anvil and also the inner portion of the welt which is unsupported by the anvil, together with the 15 upstanding edges of the welt, upper and innersole lip in the between-substance of the inseam, a lever for operating the hammer, a pivot fixed in said lever about which the hammer can swing, and means for swinging 20 the hammer widthwise of the welt to cause said upstanding edges to be rubbed outwardly.
23. A welt beating machine having, in combination, a welt support, a hammer having welt engaging face provided with converging surfaces, and means to actuate said hammer toward the welt and also over the welt to beat it and to rub it by said converging surfaces. 25
24. A welt beating machine having, in combination, a welt support, a hammer, means to actuate the hammer to beat the welt and also to move over the welt in contact therewith to rub the welt, said hammer having a rubbing face oblique to the direction of the rubbing movement for the purpose described. 30
